Application January 6, 1933, Serial No. 650,519

6 Claims. (Cl. 250—27.5)

My invention relates to electric discharge apparatus and it has particular relation to electric discharge apparatus utilized in the operation of electric discharge devices of the type incorporating a starting electrode.

The electric discharge devices utilized in the apparatus of the type to which my invention particularly applies, in general, comprise a plurality of principal electrodes between which an electrical discharge is to pass. The discharge may be initiated by impressing a large potential between these principal electrodes. However, in the practice of my invention it is initiated by the cooperation of a starting electrode and one of the principal electrodes. The starting electrode is disposed adjacent to or in contact with the principal electrode with which it is to cooperate and it generally has a resistance which is high compared to the resistance of the cooperative electrode. To start the discharge between the principal electrodes, a heavy current is transmitted between the starting electrode and its cooperative electrode.

In the electric discharge devices that are utilized in the preferred practice of my invention, at least one of the principal electrodes is a conductive liquid or a suitable solid and the starting electrode is immersed therein. When a solid is utilized it is preferably a metal of the type that has a comparatively high vapor tension at a relatively low temperature such as lead or tin.

More specifically, one of the principal electrodes in these electric discharge devices is mercury and the starting electrode is a rod of material having a resistivity high compared to mercury which is immersed in the mercury. To initiate a discharge between the principal electrodes of an electric discharge device of this type, a current is transmitted between the starting electrode and the mercury. This current is of such polarity that the starting electrode is positive electrically with respect to the mercury.

While the theory of the operation of the electric discharge devices of the type discussed hereinabove, is, largely conjectural, it appears that the discharge is initiated by the ionization effect of a series of minute sparks which pass in the space between the mercury and the starting electrode when current is transmitted through the starting electrode. It will appear at once from this consideration that to properly initiate the discharge, the starting electrode should not be wetted by the mercury nor should it amalgamate with the mercury and in experimenting with the electric dis-

charge devices discussed herein, I have verified this conclusion.

It will be seen from the above discussion that considerable care must be taken in selecting the electrodes that are utilized in the electric discharge devices and in providing for the transmission of a starting current between the starting electrode and the mercury. Since these currents are, in general, comparatively large, problems of considerable difficulty have arisen in providing the necessary starting apparatus. In accordance with the teachings of the prior art, the starting current is transmitted directly from the power source through the electrodes in question. However, since the electrode is deleteriously affected by the reverse current which must necessarily pass therethrough when the discharge is initiated between the principal electrodes, a rectifier is ordinarily connected in series with the starting electrodes in the starting circuit. The rectifier is so connected that it passes current only in a direction such that when it is energized, the starting electrode is positive relative to the mercury and by reason of the passage of current therethrough, a discharge is initiated between the principal electrodes. When the discharge is once initiated, the rectifier prevents the passage of current through the starting electrode in the opposite direction and thereby protects the electrode from the deleterious effects of the reverse current. By reason of the magnitude of the starting current, the problem of providing a suitable rectifier is not at all inconsiderable and adds to the cost and the maintenance of the system.

However, the use of the rectifier raises another difficulty which will require additional explanation here. It is to be noted that the starting electrode of the electric discharge device of the type utilized in the practice of my invention can only control the starting of the discharge and has no effect on the discharge after it is once initiated. If, for example, alternating voltage is impressed between the principal electrodes of the electric discharge device and a current is transmitted through the starting electrode at the beginning of a positive half-cycle of principal potential, the discharge is initiated. If the starting current is interrupted during this positive half cycle, it has no effect on the principal discharge and the principal discharge continues until the potential between the principal electrodes is reduced to a value below the ionization potential.

It is seen, therefore, that the output of the

electric discharge devices of the type utilized in the practice of my invention cannot be varied by varying the current transmitted through the starting electrode. It can however, be varied by 5 adjusting the point in the half cycle of positive principal potential at which the starting current is transmitted through the starting electrodes. If this point occurs early in the half cycle, the maximum current is transmitted 10 through the electric discharge device and if it occurs late in the half cycle, current of smaller magnitude is transmitted through the electric discharge device.

As has been explained hereinabove in accordance with the practice of the prior art, rectifiers are utilized in the starting circuit. Since rectifiers do not per se lend themselves with facility to phase-shift operation, the rectifiers of the type that are ordinarily utilized with electric discharge devices discussed herein are equipped with control electrodes and the phase shift is applied to the control electrodes. However, the current that must necessarily be transmitted through the rectifiers is of considerable magnitude and in consequence thereof, the rectifiers must have considerable current-carrying capacity. For this reason the grid currents transmitted by the rectifiers are not at all inconsiderable.

The phase shift is attained by varying the magnitude of a resistor or an inductor in the grid circuit. Since the magnitude of the grid current is not at all inconsiderable, it can be seen that the variation of the resistor or the inductor does not have the effect of purely shifting the phase 35 but also varies the magnitude of the grid potential and the result attained is no at all satisfactory.

It is, accordingly an object of my invention to provide for a system incorporating electric discharge devices provided with starting electrodes, starting apparatus which shall not involve the use of rectifiers.

Another object of my invention is to provide for electric discharge devices of the type incorporating starting electrodes, starting apparatus for precisely and accurately controlling the current output.

A further object of my invention is to provide for electric discharge devices of the type incorporating starting electrodes, apparatus for supplying starting current to the starting electrodes at the precise point in the half cycles of positive principal potential at which it is desirable that the starting current be supplied to provide the necessary or desirable output current.

A still further object of my invention is to provide for electric discharge devices of the type incorporating starting electrodes, simple and inexpensive apparatus for applying starting currents of high peak values but of such short duration as to require conductors of comparatively small capacity for transmission.

A more specific object of my invention is to provide for a system of the type incorporating a plurality of electric discharge devices equipped with starting electrodes, apparatus for providing starting current to the starting electrodes of a type such that the starting point of each of the electric discharge devices shall be independently adjustable.

More concisely stated, it is an object of my invention to provide for a system of the type incorporating electric discharge devices equipped with starting electrodes, apparatus for supplying the starting electrodes with current which shall

be inexpensive to install and to maintain, shall occupy little space and shall be highly tractable and easily adjustable to yield the output desired.

According to my invention the starting apparatus that I provide for electric discharge devices incorporates a plurality of capacitors. Each capacitor is associated with a starting electrode of one electric discharge device and to prepare for the initiation of a discharge in a particular device, the capacitor is charged to a high potential independently of the device. After being charged, the capacitor is connected directly between the starting electrode and the electrode cooperative therewith and the starting current is transmitted through the starting electrode and its associated element. To reduce the required current carrying capacity of the conductors through which the charging and discharging currents are transmitted, it is desirable that these currents be of as short duration as possible and for this reason as little as possible resistance is connected in series with the capacitor and the charging source and in the discharging circuit. I have found in the practice of my invention that a peak current of from 50 to 100 amperes may be attained by utilizing a capacitor of reasonable magnitude and in the ordinary charging and discharging circuits that I have utilized this peak current passes for so short an interval of time that conductors of comparatively small resistance 30 are not deleteriously affected by transmitting the current.

The novel features that I consider characteristic of my invention are set forth with particularity in the appended claims. The invention itself, 35 however, both as to its organization and its method of operation, together with additional objects and advantages thereof, will best be understood when read in connection with the accompanying drawing, in which

Figure 1 is a diagrammatic view showing a preferred embodiment of my invention, and

Fig. 2 is a view in section of a portion of an electric discharge device utilized in the practice of my invention showing a certain defective feature which might arise in the operation thereof.

The apparatus shown in Fig. 1 comprises a plurality of electric discharge devices 1 and 3, each device incorporating an evacuated chamber 5 in which a solid anode 7 of any proper material such as carbon, and a cathode 9 of mercury are disposed. A starting electrode 11 is immersed in the mercury. As has been explained hereinabove, the starting electrode 11 should have a resistivity high compared to the resistivity of the mercury 55 and should not be wetted or amalgamated with the mercury.

It will be noted that, as shown in Fig. 1, if the starting electrode 11 is not wetted by the mercury 9 and does not amalgamate therewith, the meniscus 13 of the mercury in the region in which it is in contact with the starting electrode 11 recedes from the starting electrode and a minute gap 15 is provided between the mercury and the starting electrode. According to the present theory of 60 the operation of the electric discharge devices 1 or 3, when a current is transmitted between the starting electrode 11 and the mercury 9, minute sparks are generated in the region 15 between the meniscus 13 and the starting electrode 11 and by 65 reason of the ionization produced by the minute sparks, the discharge between the principal electrodes 7 and 9 of the electric discharge devices 1 or 3 is initiated.

It is to be noted that if the starting electrode 75

11 is not of proper character and the mercury 9 amalgamates or wets the electrode, the meniscus of the mercury in the region of the electrode will assume a form such as the meniscus 17 of the 5 mercury 19 of the tube 21 shown in Fig. 2. In the electric discharge device 21 no gap is provided between the mercury 19 and the starting electrode 23 and I have found in experimenting with the electric discharge devices of the type discussed 10 herein that if such a situation exists, the starting electrode fails to function properly.

As to the proper materials which may be utilized for starting electrodes, I have found that silicon carbide, boron carbide, boron and silicon 15 yield satisfactory results. From the present state of my work with the electric discharge devices, it appears that carborundum (that is to say, silicon carbide) yields highly satisfactory results and boron carbide and boron appears to 20 be far more satisfactory even than silicon carbide.

To return to the apparatus shown in Fig. 1, the electric discharge devices 1 and 3 are energized from an alternating current power supply 25 source (not shown) through a suitable transformer 25. The secondary 27 of the transformer 25 is equipped with a plurality of terminal taps 29 and 31 and a mid-tap 33. The terminal taps 29 and 31 of the secondary 27 are connected to 30 the anodes 7 of the electric discharge devices 1 and 3 while the mid-tap 33 of the transformer 25 is connected to the cathodes 9 of the electric discharge devices 1 and 3 through the load 35 which is to be energized by the output of the 35 devices. As far as the system shown in Fig. 1 is concerned, it is, therefore, simply a full-wave rectifier which feeds a load of any character that requires unidirectional current.

A capacitor 37 is associated with each of the 40 starting electrodes 11. Each capacitor 37 is charged independently of the electrodes through the conducting segments 39 of a plurality of sectored disks 41 that are rotated in synchronism with the power source by a suitable synchronous 45 motor 43 driven from the power source. If it is assumed that the system is in the condition shown in Fig. 1, the left-hand capacitor 37 is connected in a circuit extending from the mid-tap 33 of the transformer 25 through the conducting segments 39 of one disk 41 through the left hand capacitor 37, through the conducting segments 39 of a second disk 41 to one terminal tap 31 of the secondary 27. If the conducting segments 39 are properly adjusted on their drive 50 shaft 45, a positive impulse of current will be transmitted to the left hand capacitor 37 and it will be charged to a predetermined potential.

After the capacitor 37 is so charged, the conducting segments 39 of the disks 41 through 60 which it was charged are disconnected from the brushes 47 and the capacitor 37 remains for a short interval of time in its charged condition. However, at a predetermined interval of time after this event occurs, the brushes 49 of the 65 other associated sectored disks 51 are connected to the conducting segments 53 of these disks and the capacitor is discharged through the starting electrode 11 and through the mercury 9 cooperative therewith.

70 As has been explained hereinabove, the sectored disks 41 and 51 rotate in synchronism with the power source. If the left hand capacitor 37 is now discharged at a time such that the positive half wave of potential is being applied to the 75 principal electrodes 7 and 9 of the corresponding

electric discharge device, the device is energized and current corresponding in magnitude to the point at which the device was energized is transmitted between its principal electrodes 7 and 9 and, therefore, through the load 35.

It is to be noted that the output of the electric discharge device may be adjusted by the simple expedient of shifting the segments 53 associated with the starting electrode 11 relative to the segments 39 through which the capacitor is charged. 10 As is apparent, the segments may be mounted on simple disks 51 and 41 equipped with suitable colors that are secured to the shaft 45 by set screws (not shown). To adjust the angular position of the segments 39 and 53 therefore, the 15 set screws are disengaged from the shaft 45 and the segment is suitably shifted and adjusted in its desirable position.

It is to be observed also that a shifting scheme 20 of the type shown in Fig. 3 of Patent No. 783,482, to P. H. Thomas may be utilized for adjusting the position of the sectored disks 41 and 51. In such a case, the sectored disks should not be mounted directly on the shaft of the synchronous motor 43 but they should be mounted on separate shafts which may be suitably rotated by a device such as is shown in the patent and should be driven from the synchronous motor 43 through a system of gears.

The explanation of the charging and the discharging of the capacitor 37 which has been given hereinabove, applies to the electric discharge device shown in the left-hand side of the drawing. The same explanation, of course, applies to the other electric discharge device. The discs 41 and 51 associated with this capacitor are shown in Fig. 1 in a position corresponding to that in which the capacitor 37 is discharged.

My invention has been shown herein as applied 40 to a particular system. Specifically, it has been shown as applied to a full-wave rectifying system. Its application to a half-wave rectifying system is apparent and systems wherein my invention is applied to such apparatus are equivalents which lie within the scope of my invention. It is to be noted, moreover, that my invention resides specifically in the application of a capacitor for initiating a discharge in electric discharge devices 45 equipped with starting electrodes. The sectored disk scheme for charging and discharging the 50 capacitor while it has certain considerable advantages, may, on certain occasions, be eliminated and replaced by other schemes. Apparatus in which such a replacement takes place without any change in the character of the essential elements of the system are equivalents which lie 55 within the scope of my invention.

Moreover it is to be kept in mind that while, as 60 shown and described herein, it may be advantageous to charge the starting capacitors 37 through the principal secondary 27 of the transformer 25 an auxiliary secondary may be provided for this purpose.

In certain electric discharge devices constructed 65 in accordance with the teachings of the early prior art, the discharge is initiated by impressing a potential between the starting electrode and one principal electrode in contact with each other and then separating the electrodes, thereby producing a spark. Insofar as my invention applies to devices of this type it is to be regarded 70 as including within its scope applications to these devices.

Although I have shown and described certain 75 specific embodiments of my invention, I am fully

aware that many modifications thereof are possible. My invention, therefore, is not to be restricted, except insofar as is necessitated by the prior art and by the spirit of the appended claims.

5 I claim as my invention:

1. In combination with an electric discharge device of the type incorporating a plurality of principal electrodes between which an electric discharge is to pass and a starting electrode disposed in contact with one of said principal electrodes for initiating said discharge; a capacitor, means for charging said capacitor and means for establishing a direct metallic connection from said capacitor, after it has been charged, to said starting electrode and to said principal electrode in contact therewith thereby to discharge said capacitor through said starting electrode and to initiate the electric discharge between said principal electrodes.
2. In combination with an electric discharge device of the type incorporating a plurality of principal electrodes between which a discharge is to pass and a starting electrode having an electrical resistance that is high in comparison with the resistance of one of said principal electrodes disposed in contact with said principal electrode to cooperate therewith to initiate said discharge; means for storing electrical charges, means for charging said storing means, and means for establishing a direct metallic connection between said storing means, said starting electrode and said principal electrode in contact therewith to discharge said storing means, after it has been charged, through said starting electrode and said principal electrode in contact therewith thereby to initiate a discharge between said principal electrodes.
3. In combination with an electric discharge device of the type incorporating a plurality of principal electrodes between which a discharge is to pass, at least one of said electrodes being normally a liquid, and a starting electrode immersed in said liquid to cooperate therewith to initiate a discharge; means for storing electrical charges, means for charging said storing means and means for establishing a metallic connection between said starting electrode, said liquid and said storing means to discharge said storing means, after it has been charged, through said starting electrode and said liquid thereby to initiate a discharge between said principal electrodes.

4. In combination with an electric discharge device of the type incorporating a plurality of principal electrodes between which a discharge is to pass, at least one of said electrodes being normally a liquid, and a starting electrode immersed in said liquid to cooperate therewith to initiate a discharge said starting electrode having a resistivity that is high in comparison with the resistivity of the liquid, being incapable of amalgamating with said liquid and of being wetted by said liquid, means for storing electrical charges, means for establishing a direct metallic connection between said storing means, said liquid and said principal electrode to charge said storing means and means for discharging said storing means, after it has been charged, through said starting electrode and said liquid thereby to initiate a discharge between said principal electrodes.

5. In combination with an electric discharge device of the type having a plurality of principal electrodes between which a discharge is to pass and means for initiating said discharge said means including a mercury electrode and an electrode immersed in said mercury; means for storing electrical charges, means for charging said storing means and means establishing a direct metallic connection between said storing means, said mercury and said starting electrode discharge for said storing means, after it has been charged, through said mercury and said electrode immersed therein thereby to initiate said discharge between said principal electrode.

6. In combination with an electric discharge device of the type having a plurality of principal electrodes between which a discharge is to pass and means for initiating said discharge said means including a mercury electrode and an electrode immersed in said mercury; said electrode being of a type such that it does not amalgamate with mercury nor is it wetted thereby; means for storing electrical charges, means for charging said storing means and means for establishing a direct metallic connection between said mercury electrode, said electrode immersed therein and said starting means to discharge said storing means, after it has been charged, through said mercury and said electrode immersed therein thereby to initiate said discharge between said principal electrodes.

ERNEST G. BANGRATZ.
